(57) **CLAIM**

I claim the ornamental design for a drone, as shown and described.

DESCRIPTION

FIG. 1 is a left side view of a drone showing my new design in a first configuration;

FIG. 2 is a right side view thereof;

FIG. 3 is a top view thereof;

FIG. 4 is a bottom view thereof;

FIG. 5 is a front view thereof;

FIG. 6 is a rear view thereof;

FIG. 7 is a top, rear, left side perspective view thereof;

FIG. 8 is a top, front, right side perspective view thereof;

FIG. 9 is a top, front perspective view thereof; and

FIG. 10 is a top, rear perspective view thereof.

FIG. 11 is a left side view showing the drone in a second configuration;

FIG. 12 is a right side view thereof;

FIG. 13 is a top view thereof;

FIG. 14 is a bottom view thereof;

FIG. 15 is a front view thereof;

FIG. 16 is a rear view thereof;

FIG. 17 is a top, rear, left side perspective view thereof;

FIG. 18 is a top, front, right side perspective view thereof;

FIG. 19 is a top, front perspective view thereof; and

FIG. 20 is a top, rear perspective view thereof.

FIG. 21 is a left side view showing the drone in a third configuration;

FIG. 22 is a right side view thereof;

FIG. 23 is a top view thereof;

FIG. 24 is a bottom view thereof;

FIG. 25 is a front view thereof;

FIG. 26 is a rear view thereof;

FIG. 27 is a top, rear, left side perspective view thereof;

FIG. 28 is a top, front, right side perspective view thereof;

FIG. 29 is a top, front perspective view thereof; and

FIG. 30 is a top, rear perspective view thereof.

(Continued)

FIG. 31 is a left side view showing the drone in a third configuration; (56)

FIG. 32 is a right side view thereof;

FIG. 33 is a top view thereof;

FIG. 34 is a bottom view thereof;

FIG. 35 is a front view thereof;

FIG. 36 is a rear view thereof;

FIG. 37 is a top, rear, left side perspective view thereof;

FIG. 38 is a top, front, right side perspective view thereof;

FIG. 39 is a top, front perspective view thereof; and,

FIG. 40 is a top, rear perspective view thereof.
